UNITED STATES PATENT OFFICE.

WILLIAM L. PAUL, OF DAVIS, NORTH CAROLINA.

WHISTLE ATTACHMENT FOR GAS-ENGINES.

SPECIFICATION forming part of Letters Patent No. 757,673, dated April 19, 1904.

Application filed October 8, 1903. Serial No. 176,268. (No model.)

To all whom it may concern:

Be it known that I, WILLIAM L. PAUL, a citizen of the United States, residing at Davis, in the county of Carteret and State of North Carolina, have invented certain new and useful Improvements in Whistle Attachments for Gas-Engines; and I do hereby declare the following to be a full, clear, and exact description of the invention, such as will enable others skilled in the art to which it appertains to make and use the same.

My invention relates to an attachment for gas-engines or the like; and it consists of certain novel features of combination and construction of parts the preferred form whereof will be hereinafter clearly set forth.

The prime object of my invention, among others, is to utilize the exhaust from a gas-engine with the employment of a minimum number of parts, each part possessing great simplicity, thereby making it possible to produce my invention in complete operative condition at a small cost.

Other objects and advantages will be hereinafter made clearly apparent, reference being had to the accompanying drawings, which are made a part of this application, and in which—

Figure 1 shows a side elevation of my invention as applied to an ordinary gas-engine. Fig. 2 is a longitudinal central section of my attachment, showing the relative position of the whistle and means for operating the same. Fig. 3 is a horizontal section of Fig. 2 on line 3 3, while Fig. 4 is a detail view showing the operating-crank for controlling the travel of the exhaust.

The details of my invention and coöperating accessories will for convenience be designated by numerals, the same numeral applying to a similar part throughout the several views.

Referring to the numerals on the drawings, 1 indicates the base portion usually employed in supporting the engine proper, 2, designed to be actuated by successive explosions of gas, while 3 designates the tubular body of my exhaust tube or port. The exhaust-tube 3 is divided transversely by the formation of a valve-seat 4, designed to receive the valve 5, which

is carried by the valve-stem 6, the latter being vertically disposed in suitable bearings provided by the brackets 7 and 8, as clearly shown in Fig. 2.

The lower end of the stem 6 is operatively connected to the crank-arm 9 on the crank-shaft 10 by means of the link-section 11, it being understood that said crank-shaft is provided with a suitable bearing or supporting bracket 12 at its outer end, attached to the lower side of the auxiliary chamber 13, the opposite end of said crank-shaft being arranged to pass through suitable stuffing-boxes 14 and 15, whereby the escape of products of gas combustion will be prevented. The lower end of the tubular exhaust or pipe 3 is properly connected with the exhaust-chamber 16, as by having its end threaded in a suitable aperture, as shown in Fig. 2.

It will be observed by reference to Fig. 2 that the auxiliary chamber 13 may be cast or otherwise formed integral with the exhaust-tube 3, it being understood that the lower end of the auxiliary chamber 13 shall be placed in communication with the chamber in the exhaust-tube 3 below the valve-seat 4. I also provide for the lower end of the auxiliary chamber 13 a valve-seat 17 and the valve 18 adapted to fit into the upper side of said seat, said valve 18 having a suitable guiding-stem 19 seated in an aperture in the supporting-brackets 20 and 21. I also provide a shoulder or collar 22 and secure it to the stem 19 intermediate the brackets 20 and 21, and it is obvious that by locating the spring 23 around the stem between the bracket 21 and the fixed collar or shoulder 22 the valve will be held normally downward or in its seat 17, and thereby in a closed position. I also arrange to hold the valve 5 normally downward or in an open position by means of the arm 24, controlled by the spring 25, as more clearly shown in Fig. 4, said arm 24 being secured in proper relationship by the set-screw 26, as will be obvious.

In Fig. 2 of the drawings it will be observed that the valve 5 has been closed by a proper rotation of the crank-shaft 10 through the mediation of the handle 27, thereby closing the upward movement of the exhaust products

of combustion and directing them laterally into the lower end of the auxiliary chamber 13 and the force thereof under pressure will overcome the tension of the spring 23 and 5 raise the valve 18 out of its seat, thus permitting such products to pass into the upper end of the auxiliary chamber 13 to become sufficiently condensed or under pressure to operate the whistle 28, as will be obvious.

10 When it is desired to discontinue blowing the whistle, all that is necessary to be done by the operator is to partially rotate the crank-shaft 10 through the mediation of the handle 27, which will draw the crank-arm 9 downward and incidentally lower the valve 5 and open a way for the exhaust to pass directly upward through the tubular vent or casing 3 and thence into the open air. It is therefore obvious that the whistle 28 may be operated at

15 20 will by simply partially rotating the crank-shaft 10 sufficiently to raise the valve 5, and thereby divert the movement of the products of gas combustion into the auxiliary chamber 13 to overcome the tension of the spring 23

25 and provide a passage-way through said auxiliary chamber into operative communication with the whistle.

It will thus be seen that I have provided very simple though reliably efficient mechanism for utilizing the exhaust products of combustion of a gas-engine, and while I have described the preferred combination and construction of parts deemed necessary in carrying out my invention I desire to comprehend 30 such equivalents and substitutes as may be regarded as falling fairly within the scope of my invention.

Believing that the advantages and manner of constructing and using my whistle attachment for gas-engines or the like have been 35 made clearly apparent, further reference to the details is deemed unnecessary.

What I claim as new, and desire to secure by Letters Patent, is—

1. The herein-described means for storing 45 and utilizing the exhaust of gas-engines to blow a whistle, comprising the combination with a gas-engine cylinder, of an exhaust tube or port 3, an auxiliary storage-chamber 13, said auxiliary chamber communicating with 50 said exhaust-port 3, a valve 5 located in said port 3, having a stem 6, a shaft having a crank-arm, a link connecting said crank-arm and stem 6, means to partially rotate said shaft whereby said valve 5 may be opened or closed, 55 a valve 18 in the auxiliary chamber 13 and means to hold said valve normally closed, and a whistle communicating with said auxiliary chamber, as set forth.

2. In combination with the cylinder of a 60 gas-engine, of an exhaust-chamber 3, an auxiliary chamber 13 formed integral therewith, said chambers having a communicating passage, a valve 5 located in said exhaust-chamber and above said communicating passage, 65 whereby when said valve is closed the exhaust-gases will be forced through said passage into the auxiliary chamber 13, a valve 18 at the lower end of said auxiliary chamber adapted to be opened by the pressure of the 70 exhaust-gases, a stem for said valve, brackets designed to receive said stem and retain the valve in place, a spring surrounding said stem between said brackets, designed to close said valve 18 when the valve 5 is opened, and a 75 whistle communicating with said auxiliary chamber, as set forth.

In testimony whereof I affix my signature in presence of two witnesses.

WILLIAM L. PAUL.
